UNITED STATES PATENT OFFICE.

JOSEPH NEU, OF LOS ANGELES, CALIFORNIA.

DESIGN FOR A SIGNAL FACEPLATE.

Application filed January 24, 1927. Serial No. 20,477. Term of patent 7 years.

To all whom it may concern:

Be it known that I, JOSEPH NEU, a citizen of the United States, residing in Los Angeles, county of Los Angeles, and State of California, having a place of business at 609 California Bank Building, Los Angeles, California, have invented a new, original, and ornamental Design for Signal Faceplate, of which the following is a specification, reference being had to the accompanying drawing, forming part thereof.

Figure 1 is a front or face view of a signal face plate embodying the design.

Figure 2 is a perspective view of the signal face plate.

What I claim is:

The ornamental design for a signal faceplate substantially as shown.

JOSEPH NEU.
